MANDREL ASSEMBLY

Peter R. Aronson, Millburn, N. J., assignor to
Oxweld Acetylene Company, a corporation of
West Virginia

Application December 31, 1938, Serial No. 248,725

12 Claims. (Cl. 78—103)

This invention relates to the art of metal working and particularly to a mandrel assembly for use with ductile metal blanks having rough, oversize passages therethrough, and which are adapted to be subjected to metal-working operations to form blowpipe nozzles and the like.

One process of making blowpipe nozzles comprises swaging blanks of copper bar-stock into the form of the completed nozzle. The blanks are provided with longitudinally drilled rough, oversize passages including a central oxygen passage and a series of preheat passages, in all of which passages, mandrels in the form of music wire are inserted. One such method is disclosed in United States patent application Serial No. 158,703 filed August 12, 1937, by P. R. Aronson. By virtue of the swaging operation, the length of the metal blank is increased, and its cross-sectional area as well as that of the rough oversize passages is reduced,—the latter conforming with the cross-section of the wire mandrels.

Blowpipe nozzles have also been produced by pressure-forming metal blanks of the above-described type having wire mandrels within the oxygen and preheat passages thereof. This latter method comprises the continued forcing of a blank mounted on a mandrel assembly into a die having substantially the form of the finished nozzle. One form of making blowpipe nozzles in accordance with this latter method is disclosed in United States patent application Serial No. 168,144 filed October 9, 1937, by Chalmers K. Bryce et al.

When it is desired to produce blowpipe nozzles in accordance with methods of the above-described type, especially on a commercial basis, production costs can be greatly reduced if the mandrels can be used over and over for many hundreds of times; if the blanks can be mounted upon the mandrel wires with a minimum of effort and time; and if the mandrels can be extracted without injury from the swaged or pressure-formed nozzle.

An object of this invention is to provide a mandrel assembly of simple construction and capable of overcoming the above and other difficulties. Other objects include, the provision of a mandrel assembly with means for facilitating the mounting of metal blanks thereon; the provision of such a mandrel assembly in which the mandrels are designed and constructed so that they can be repeatedly used without failing; the provision of a combined mandrel assembly and punch for supporting a metal blank during a

pressure-forming operation; and the provision of a combined mandrel assembly and punch capable of interchangeably supporting in accurate relation a plurality of wire mandrels of different effective size.

The above and other objects and novel features of this invention will become apparent from the following specification considered in connection with the accompanying drawing in which:

Fig. 1 is an end elevational view of a mandrel assembly constructed in accordance with the principles of this invention;

Fig. 2 is a top plan view, partly in section, of the assembly shown in Fig. 1;

Fig. 3 is a sectional view taken along line 3—3 of Fig. 1;

Fig. 4 is an end elevational view of a modified form of mandrel assembly constructed in accordance with this invention;

Fig. 5 is a sectional view taken along line 5—5 of Fig. 4;

Fig. 6 is an end elevational view looking at the right-hand end of the assembly shown in Fig. 5;

Fig. 7 is an end elevational view of another modified form of mandrel assembly constructed in accordance with this invention; and

Fig. 8 is a sectional elevational view taken along line 8—8 of Fig. 7.

Referring to Figs. 1, 2 and 3, a head 10 of bronze or other ductile metal is provided with accurately spaced passages extending longitudinally therethrough for receiving a series of mandrel wires 12 which may be formed from music wire or heat-treated drill-rod stock. The number and arrangement of the passages within the head 10 correspond with the number of preheat passages as well as the central oxygen passage within a ductile metal blank 11 to be subjected to a swaging or pressure-forming operation. Certain of the mandrels 12 are cut in lengths sufficient to be formed into U-shaped elements, each leg of which constitutes a mandrel for a passage within the metal blank 11. The head 10 is further provided with a recessed end portion 14, and in the embodiment shown, two U-shaped elements are mounted in the head 10 so that the legs of each extend beyond the one end thereof. The portion of each U-shaped element, which connects the respective legs 12, seats within the recess 14 in a manner so that it does not extend beyond the end of head 10 in which said recess 14 is located.

Referring to Fig. 3, one of the mandrels 12, adapted to fit within the central or oxygen passage of the blank 11, is positioned within a

central passage 13 within head 10. The oxygen passage mandrel 12 is of the same wire that the other mandrels are, and it is bent into a general U-shaped element with one leg 15 substantially shorter than the other. This short-legged U-shaped element is fed into a pair of the passages including the passage 13 within head 10, and the short leg 15 is bent at right angles to the other leg and fits along the end of the head 10 opposite to that in which recess 14 is located.

The head 10, with its assembly of mandrels, is then fed (head first) into a swaging machine to effect a rigid grip between the head and each of the wire mandrels, and/or the recess 14 may be filled with solder.

For the purpose of facilitating the mounting of the blank 11 on the mandrel wires 12, a spacer or spreader 16 is provided. It comprises a cylindrical piece of aluminum drilled with holes equal in number and corresponding in location to the passages within the blank 11 and the head 10. The size of the holes in the aluminum spreader are such that it freely slides over the mandrel wires 12. By positioning the spreader 16 near the free end of the mandrel wires 12, the latter may be readily inserted into the passages within blank 11.

The embodiment of the invention disclosed in Figs. 1, 2 and 3, illustrates an arrangement whereby five mandrels are employed. It is to be understood that any number and arrangement of mandrels may be employed in constructing an assembly in accordance with the teachings of the invention.

When it is desired to produce a swaged or pressure-formed blowpipe nozzle of the type employing a low-pressure, high-volume oxygen stream, a different form of mandrel assembly is necessary in order to provide a sufficiently large central oxygen passage within the nozzle blank capable of accommodating a low-pressure large-volume oxygen jet. Referring to Figs. 4, 5 and 6, a modified form of mandrel assembly is disclosed in which a head 18 is substantially identical with the head 10 of Fig. 2 in that it is adapted to support a series of mandrel wires 20 identical with, and in the same manner as the wires 12 of Fig. 2 are supported. The wires 20 serve in the present instance as mandrels for the preheat passages within a metal blank 22. The head 18 is provided with a relatively large central passage 24 adapted to receive a mandrel 26 the cross-section of which is substantially greater than that of the wire mandrels 20. The mandrel 26 is provided with a head 23 adapted to seat within the recess of head 18; a shank portion 25 of constant cross-section adapted to accurately fit within passage 24; and a tapered portion 27 adapted to fit within the relatively large central oxygen passage of the blank 22. Because of its tapered construction, the mandrel 26 is easily withdrawn from the blank 22 after the swaging operation. A spreader or spacer 28, similar to the spacer 16 of Fig. 2, is adapted to slidably fit the mandrel wires 20. It is provided with a sufficiently enlarged central passage 29 to enable its movement longitudinally of the wires 20 without interfering with the tapered mandrel 26.

When it is desired to produce a blowpipe nozzle in accordance with the pressure-forming method referred to, a still further modified form of mandrel assembly is employed. Referring to Figs. 7 and 8, a head 30, which functions as a combined punch and mandrel support, is provided with an elongated portion 32 ground peripherally to pro-

vide an accurate sliding fit with a guide portion of a die within which the metal blank is adapted to be forced. The head 30 is also provided with a portion 34 constructed in a manner to facilitate its engagement with the gripping element of a power press. The portion 34 comprises a relatively thick flange integral with the elongated body portion 32, and it is arranged to be received by the gripping element of the press.

Mandrels 36, equal in number to the passages within a metal blank 37 to be formed, are removably held in the head 30 in positions corresponding to the relative locations of the passages within the metal blank 37. The design and construction of the mandrels 36 are such as to lessen the frictional force set up between them and the cold-flowing metal of blank 37 during the pressure-forming operation. They may be constructed of cold-drawn wire, and provided with a shank portion, equal in length to the overall length of the head 30. The forward portion of each mandrel 36 is preferably tapered in the direction of the flow of metal during the pressure-forming operation. The tapered construction of the mandrels, together with the fact that they are made from cold-drawn wire, lessens the frictional force set up between the cold-flowing metal and the mandrels. This is apparently due, at least in part, to the longitudinal arrangement of the grain structure of the cold-drawn wire from which they are made. A bronze knob 38 is welded or swaged to the shank end of each mandrel 36. The welding of the bronze knob to the steel mandrel wire does not affect the hardness and flexibility of the wire because the temperature necessary to effect a bronze weld is well below that temperature which would cause a metallurgical change in the steel wire. When it is desired to swage the knob 38 onto the shank end of a mandrel 36, the latter is roughened or knurled in order to insure a good grip between the knob and mandrel.

The mandrel wires 36 are adapted to be positioned within accurately arranged passages 39 within the head 30. The passages 39 correspond with the number and location of the passages within the metal blank 37. The bronze knob 38 of each mandrel 36 is adapted to be received within a counterbore 41 formed within the face of the flanged end 34 of head 30. The head 30 may be employed with mandrels having effective portions of different size since the cross-section of the mandrel shank portions as well as that of the knobs 38 may be the same for mandrels of different effective size.

A sliding spacer element 40 having passages 43 equal in number to, and located in corresponding positions with, the passages within blank 37, is slidably positioned on the mandrel wires 36. It facilitates the assembly of the metal blank 37 onto the mandrels 36 in the same manner as the spacers 16 and 28 function.

Although the various features of the mandrel assembly have been shown and described in detail to fully disclose several embodiments of this invention, it will be evident that numerous changes may be made in details and certain features may be used without others, without departing from the principles of the invention.

What is claimed is:

1. A mandrel assembly for use with a metal blank having a plurality of passages therethrough and adapted to be subjected to a metal-working operation, comprising in combination, a series of wire mandrels; a head adapted to rigidly hold at least a portion of said wire mandrels in fixed

spaced relation; and spacer means mounted on said wire mandrels for facilitating mounting of said metal blank upon said wire mandrels preparatory to said metal-working operation.

5. 2. A mandrel assembly as claimed in claim 1, in which said wire mandrels include at least one U-shaped wire, each leg of which constitutes a mandrel for a passage within said metal blank.

10. 3. A mandrel assembly as claimed in claim 1, in which said head is provided with passages equal in number to, and located in accordance with passages within said metal blank.

15. 4. A mandrel assembly as claimed in claim 1, in which said wire mandrels include at least one U-shaped wire, and said head is provided with a recessed end adapted to receive the portion of said U-shaped wire that joins the respective legs thereof, whereby said portion does not protrude beyond the end of said head which is recessed.

20. 5. A mandrel assembly as claimed in claim 1, in which the means mounted on the wire mandrels for facilitating mounting a blank thereon comprises a spacer having a series of passages equal in number, and spaced in accordance with

25. the location of the passages within said blank, and in which said spacer is adapted to slidably engage said wire mandrels.

6. A mandrel assembly as claimed in claim 1, in which said head and spacer means are each 30 provided with an aligned central passage adapted to receive and position a central mandrel of substantially greater diameter than said wire mandrels.

35. 7. A mandrel assembly as claimed in claim 1, in which said head and spacer means are each

provided with an aligned central passage; and in which a tapered mandrel, having a greater diameter than said wire mandrels is positioned within said central passages, the size of the central passage within said spacer being such that said spacer will not interfere with said tapered mandrel when it is used to facilitate mounting of a metal blank onto all of said mandrels.

5. 8. A mandrel assembly as claimed in claim 1, in which said head comprises an elongated shank 10 portion and a press-gripping portion.

15. 9. A mandrel assembly as claimed in claim 1, in which said head comprises an elongated shank portion and a press-gripping portion, and in which said portions are provided with a series of 15 passages adapted to interchangeably receive wire mandrels having effective portions of different size and adapted to position the same in predetermined spaced relation.

20. 10. A mandrel assembly as claimed in claim 1, 20 in which said wire mandrels are provided with means cooperating with said head so that they may be removed from said head only by movement in one direction.

25. 11. A mandrel assembly as claimed in claim 1, 25 in which each of said mandrels is provided at one end with a bronze knob adapted to cooperate with said head.

30. 12. A mandrel assembly as claimed in claim 1, in which said head is provided with a series of 30 elongated passages counterbored at one end for receiving knobs connected to the one end of each mandrel wire, whereby said knobs do not protrude beyond the counterbored end of said head.

PETER R. ARONSON. 35
